UNITED STATES PATENT OFFICE.

GEORGE H. FORSYTH, OF CHICAGO, ILLINOIS, ASSIGNOR TO WAUGH DRAFT GEAR COMPANY, A CORPORATION OF ILLINOIS.

RAILWAY DRAFT-RIGGING.

1,081,298.

Specification of Letters Patent.

Patented Dec. 16, 1913.

Application filed July 16, 1904. Serial No. 216,829.

To all whom it may concern:

Be it known that I, GEORGE H. FORSYTH, a citizen of the United States, residing at Chicago, in the county of Cook and State 5 of Illinois, have invented certain new and useful Improvements in Railway Draft-Rigging, of which the following is a specification.

This invention relates to draft rigging for railway cars, and more especially to that type of draft rigging wherein there are provided transversely-disposed and longitudinally-movable members adapted to receive the strains of buffing and draft and to transmit the same to abutting stop elements attached to the car. In this class of mechanism the resistance medium, consisting of spring, friction or other suitable elements having a limited yielding capability, is interposed between said movable members; while fastened to the end of the draw-bar and generally embracing the draft mechanism as a whole is the yoke or yoke-strap. As a result of this disposition of parts the 25 movable members above mentioned, which are commonly termed followers, normally contact at their central portions with the ends of the draw-bar and yoke-strap. Consequently, when the draw-bar is in a central position relatively to the car, the strains of buffing and draft are evenly applied to the adjacent followers throughout the width of the draw-bar and yoke-strap. When, however, the draw-bar is drawn to one side 30 as on curves, the buffing and draft strains are temporarily concentrated on one side of the central axis of the resistance medium. This not only injures the yoke but tends to throw one of the followers into an oblique or canted position, with the result that the strains of buffing and draft are unevenly applied to the resistance medium. If the latter is the ordinary coil-spring there results a buckling of the same; whereas, if it consists of a friction mechanism, the friction elements are subjected to unequal wear and the resisting capacity of the draft rigging is proportionately lessened. Furthermore, the application of greater force to one side 45 of the draft rigging than to the other results in uneven strains upon and possible breaking of or injury to the stop elements which are attached to the car and receive the strains transmitted by the followers.

55 My present invention aims to overcome

the above objections found in present practice by providing means whereby the strains of buffing and draft on curves as well as on straight track are not only applied in such a manner as not to injure the yoke, 60 but to maintain the followers in substantial parallelism to each other, thereby distributing all strains evenly throughout the elements of the draft rigging.

Broadly speaking, I accomplish these objects not merely by always applying the buffing and draft strains on or closely adjacent to the longitudinal axis of the resistance medium, but by a construction and arrangement whereby said strains are not 65 allowed to operate wholly on the side of the longitudinal axis of the resistance medium to which the draw-bar is drawn, but operate on both sides of said longitudinal axis so as to prevent the follower from assuming an 70 angular position relative to its companion follower.

In other words, my invention consists in the association or combination with a draw-bar and a follower or equivalent element 80 of a draft rigging capable of angular movement relatively thereto, of means whereby when the draw-bar is drawn to one side the strains of buffing and draft operate upon the draft rigging through such a distribution 85 of force on both sides of the longitudinal axis of the resistance medium as to prevent substantial angular movement of the follower or equivalent member or any distortion of the parts of the draft rigging with the injury consequent upon such distortion. Heretofore, so far as I am aware, this general 90 result has been attained only by having the draft rigging mechanism as a whole pivot and swing with the draw-bar. Such a 95 method necessitates a radical departure from generally accepted and standard constructions in railway equipment in which the transverse and longitudinally-movable members or followers are capable of angular 100 movement relatively to the draw-bar, and are adapted to successively abut stop elements attached to the car.

In the accompanying drawings I have illustrated one practical form in which my 105 invention may be embodied; and referring thereto,—Figure 1 is a top plan view of a draft rigging mechanism embodying my present improvement; Fig. 2 is a similar view of the same mechanism showing the 110

relative positions assumed by the parts under a buffing strain when the draw-bar is drawn to one side as on a curve: Fig. 3 is a view similar to Fig. 2 showing the relative 5 positions assumed by the parts under a draft strain when the draw-bar is drawn to one side as on a curve: Fig. 4 is a longitudinal vertical sectional view of the parts as they appear in Fig. 1; Fig. 5 is a front end view 10 of Fig. 1; and Figs. 6 and 7 are plan and elevation details showing construction and arrangement of parts for economizing space between the end of the draw-bar or yoke and an adjacent follower.

15 Referring to the drawings, 10 designates the parallel draft-sills or timbers, which may be the center-sills of the car-body or draft-timbers secured to the under side of said center-sills. As herein represented, 20 they are the steel channel center-sills of a car-body.

11 designates the transverse top plate uniting the forward ends of the sills, and 25 12 designates an inverted hanger or draw-bar support secured to the under sides of the center-sills at their forward end. Secured to the inner faces of the draft-sills 10 are the usual front and rear stop elements 10 are the usual front and rear stop elements 13 and 14, respectively.

30 15 designates the draw-bar which lies between the draft-sills 10, its forward portion resting on the support 12, and its rear end having attached thereto the usual draw-bar extension or yoke-strap 16, this latter embracing the front and rear followers 17 and 35 18, respectively. Between the inner faces of said followers is interposed a resistance medium, here shown for the sake of simplicity and convenience as consisting simply 40 of the usual heavy coil-spring 19.

Centrally of the outer face of the front follower 17 I provide a rounded or convexed protuberance 17^a, and to the inner end of the draw-bar 15, between the upper and lower 45 sections of the yoke, I attach a block 20, the inner face of which is concave on a curve of substantially the same radius as the curve of the protuberance on the follower, as shown at 20^a, excepting that the ends of the 50 concavity are slightly reversely curved, as shown at 20^b, to prevent the formation of anything like a sharp edge which might bite into the convex surface of the follower and tend to retard free relative sliding 55 movement between said convex and concave surfaces under the lateral swing and subsequent thrust or pull of the draw-bar. The rear follower 18 is provided with a convexed protuberance 18^a corresponding in all respects with the protuberance 17^a of the follower 17; and the rear closed end of the yoke is also provided with a block 21 which has a concave face 21^a, reversely curved at its 60 ends at 21^b, similar in all respects to the formation of the concave face of the block 20.

The block 20 is preferably secured to the inner end of the draw-bar by means of a vertically-apertured lug or boss 20^c which enters the end of the hollow draw-bar and is secured by one of the usual bolts 22 by 70 which the yoke is attached to the inner end of the draw-bar proper. The rear block 21 may be conveniently secured in the yoke by a bolt 23 passed through a vertical aperture in the block and registering apertures in the 75 top and bottom of the yoke, as clearly shown in Fig. 4.

The operation of the mechanism is fairly illustrated by Figs. 1, 2 and 3 which show the relative positions assumed by the parts under different stresses. In Fig. 1 the parts are shown as they appear when idle, wherein it will be seen that the concave faces of the filling-blocks 20 and 21 contact the convex faces of the followers 17 and 18, respectively, for a considerable extent on both sides of the central longitudinal axis of the resistance medium and throughout substantially the entire extent of said concave surfaces.

From this it is evident that under the 80 application of a draft or buffing strain in the direction of the draw-bar as shown in Fig. 1, such as would occur on a straight track, the rear or front follower, as the case may be, will simply be moved away from its co-operating stops without relative angular movement to the draw-bar or to its companion follower, and without consequent distortion of the resistance medium or unequal strains upon the stops. This, of course, occurs on straight track with the ordinary and standard type of draft rigging hereinabove referred to.

When draft and buffing strains are imparted on curves, however, in the case of the ordinary draft rigging at present 90 extensively in use, such strains are imparted to the movable follower in such a way as to cant the follower or cramp the resistance medium. My invention obviates these 95 objections, as will be seen by reference to Figs. 100 2 and 3 of the drawings, in connection with which the following operations occur.

Considering first a buffing strain on a curve, as illustrated by Fig. 2, when such strain occurs, the concave face 20^a of the forward 110 filling-block undergoes a slight relative sliding movement over the convex face of its co-operating follower 17, whereby substantially the same extended surface of contact between said parts is maintained, there being 115 a substantial contact on both sides of the center of the follower and on both sides of the center of the longitudinal axis of the resistance medium, the co-operating faces of the rear follower and rear filling-block being 120 separated, as shown, and the entire draw-bar and its yoke undergoing a slight bodily lateral movement.

In the case of a draft strain applied on a curve, as illustrated in Fig. 3, the co-operat- 130

ing faces of the front follower and forward filling-block are separated, while between the coöperating curved faces of the rear follower and rear filling-block there occurs 5 a slight combined sliding and pivotal movement, which very slightly changes the contact relations of said surfaces but still preserves a substantial surface of contact on both sides of the center of the follower and 10 on both sides of the axis of the resistance medium. Consequently, in this case, as well as in the case illustrated in Fig. 2, the strains are substantially uniformly distributed, with the result that the follower 15 moves toward its companion follower without substantial change in its parallel relation thereto, which thus obviates any cramping of the resistance medium and effects an equal and uniform distribution of the 20 strains through the ends of the companion follower upon its coöperating stops. It will thus be seen that the protuberances 17^a and 18^a constitute yieldable means disposed between the two ends of the yoke for guiding the latter in its lateral movements.

In Figs. 6 and 7 I have shown in detail a manner of constructing the engaging parts of a filling-block and follower whereby to economize the space intervening between the end of the draw-bar or yoke and an adjacent follower. As shown in said figures the filling-block 20 extends less than the full height of the interior vertical dimension of the yoke and its concave bearing 35 surface lies within the outer surface of the follower, the coöperating convex bearing surface of the follower being formed in a recess within the outer surface of the follower. It is understood that this is only 40 one of a number of ways that might be employed to accomplish the object desired.

In addition to the advantages hereinabove pointed out, it may be mentioned that the mechanism is self-centering, and automatically acts to restore the draw-bar to normal or central position whenever released from draft or buffing strains, thus doing away with the necessity of providing independent or separate centering devices, 45 some centering means being necessary for coupling purposes where considerable side clearance is allowed. My invention also obviates a frequent source of injury to the draw-bar and yoke connection. Heretofore 50 it has been customary in practice to provide some kind of rigid guide to maintain the yoke within limited lateral bodily displacement relatively to the longitudinal median line of the car. The objections to this have 55 been that during angular movement of the yoke on curves, either the yoke has tended to engage and bind on the guides, or the latter have become fulcrum points tending to displace the normal pivotal center of the 60 yoke during buffing or draft. The latter is

particularly true where the draw-bar has been allowed an increased amount of side clearance. Where the draw-bar is riveted rigidly to the yoke, the yoke guides have operated to transmit excessive transverse shearing strains to the rivets that secure the yoke to the draw-bar. My present invention obviates this objection in that the yoke is not confined laterally by rigid guides, but by yielding guides which, as hereinabove 70 pointed out, in coöperation with the resistance medium tend to re-center the yoke when free from buffing or draft strains, the yielding guides in the particular embodiment of the invention shown in the drawing 75 being the coöperating curved surfaces on the followers and draw-bar and yoke under the influence of the co-acting spring.

While I have shown and described one mechanical form in which my invention 80 may be embodied, and which I have found by actual tests to satisfactorily yield the results hereinabove described, yet I desire it to be understood that, in its broader aspects, the invention is by no means limited to the 85 particular means shown and described for effecting these results.

I claim:

1. In a draft-rigging mechanism, the combination with a resistance medium and 90 an angularly-movable draw-bar, of a follower interposed between said draw-bar and resistance medium and provided with a curved convex surface engaged by the draw-bar, when the latter is moved laterally, on 95 the side opposite that to which the draw-bar is moved, substantially as described.

2. In a draft-rigging mechanism, the combination with a draw-bar, of a member 100 adapted to receive therefrom the strains of buffing, said member having a convex inset 105 surface coöperating with the draw-bar, substantially as described.

3. In a draft-rigging mechanism, the combination with a draw-bar, of a member 110 adapted to receive therefrom the strains of buffing, said member having an inset surface coöperating with the draw-bar, said inset surface being of less than the full height of the member, substantially as described.

4. In a draft-rigging mechanism, the combination with a draw-bar and a follower having respectively concave and convex engaging surfaces so formed and co-operating that when the draw-bar is under strains of buffing in a sidewise position the strains are distributed on both sides of the axis of the resistance medium, said coöperating surfaces lying within the thickness 120 of the follower and being of less than the full height of the follower, substantially as described.

5. In a draft-rigging mechanism, the combination with a draw-bar, of a filling- 125

block having a stem or shank entering an aperture in said draw-bar and secured by a pin passed therethrough, substantially as described.

- 5 6. In a draft-rigging mechanism for railway cars, the combination with the draft sills, of follower plates supported on the draft sills, spring mechanism between the follower plates, yoke straps engaging
10 about the follower plates, contact blocks secured between the yoke-straps, a gradually

rounding convex extension from each follower plate, a pocket in each contact block into which the convex extension of the adjacent follower plate extends, each pocket having two bearing surfaces in tangential engagement with the convex extension, substantially as described. ¹⁵
